US0D1089534S

(12) **United States Design Patent** (10) **Patent No.:** **US D1,089,534 S**
(45) **Date of Patent:** **** Aug. 19, 2025**

(54) **FLUID EMITTING DEVICE**

- (71) Applicant: **Kao Corporation**, Tokyo (JP)
- (72) Inventors: **Susumu Fujinami**, Tokyo (JP); **Meri Hozumi**, Tokyo (JP); **Hirokatsu Sugawara**, Tokyo (JP); **Soko Tagaya**, Tokyo (JP)
- (73) Assignee: **Kao Corporation**, Tokyo (JP)

(**) Term: **15 Years**

(21) Appl. No.: **29/914,427**

(22) Filed: **Oct. 17, 2023**

(30) **Foreign Application Priority Data**

- Apr. 17, 2023 (JP) ..... 2023-007917 D
- (51) **LOC (15) Cl.** **23-01**

(57) **CLAIM**

The ornamental design for a fluid emitting device as shown and described.

DESCRIPTION

FIG. 1 is a reduced-scale front, left side, top perspective view of a fluid emitting device showing our new design thereof;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

The broken lines in the drawings and the areas within them depict portions for a fluid emitting device that form no part of the claimed design.

1 Claim, 7 Drawing Sheets
